APPARATUS FOR PARTIALLY DRYING
MOIST CLAY BODIES

Laurence J. Dykstra and Edwin M. Meyer, Rochester, N. Y., assignors to Victor Insulators, Inc., Victor, N. Y., a corporation of New York

Application November 5, 1940, Serial No. 364,438

1 Claim.

(Cl. 34—233)

This invention relates to an apparatus for partially drying moist clay bodies, with more particular reference to the treatment of thick clay pugs after they come from a pugmill during the manufacture of porcelain insulators or the green clay insulator bodies after they have been turned or otherwise shaped, previously to firing in a kiln, and it has for its purpose to afford an apparatus by which the necessary moisture-removing operation can be carried on successfully and efficiently in a much shorter period of time than is possible with the apparatus now in use and without the losses attendant upon conventional practices, due to cracking of the insulator surfaces or complete breakage when subjected to heat of the kiln.

The common method of drying clay bodies in the insulator industry is to place the clay pieces in a room where they are subjected to currents of hot air that are first passed over steam coils, a procedure that requires a week or more to remove the amount of moisture that must be taken out before the clay is ready for the kiln treatment. According to this old method, it is necessary to apply heat very slowly and to control humidity accurately in order to prevent forming a crust at the surface of the clay and consequent excessive shrinking and cracking, or complete breakage when subjected to the heat of a kiln, and it is a particular purpose of this invention to remove moisture from a clay body in such a manner that there is no likelihood of cracking the surface, or bursting the clay body upon application of the intense heat of the kiln, and to bring about the required drying in from six to seven hours, or little more than one-fourth of a day as compared with a week or more under the general practices heretofore followed.

The difficulty with drying a moist clay body by means of hot air or heat convection currents is that when applied in this manner, the heat is driven from the outside or surface of the clay body inwardly to its interior by the air currents and consequently the surface of the clay is likely to reach a higher temperature than the interior and removal of moisture takes place at a faster rate than it migrates from the interior to the surface. As a result, crusting of the surface takes place, causing excessive shrinking of the outer strata and cracking, or explosion of the clay body when it is subjected to kiln treatment, and the present invention overcomes this difficulty by using only radiant energy, preferably in the form of infra-red heat rays, to cause migration of the moisture from the interior of the clay body to its surface, and simultaneously removing surface moisture by a current of air at a temperature that is somewhat lower than the temperature of the clay body produced by the radiant energy, the air current acting merely to evaporate or re-

move the surface moisture always at a rate somewhat slower than that at which it migrates from the interior of the clay body to the surface and without raising the temperature of the clay, thus effectively preventing the formation of a surface crust and insuring the maintenance of a uniform moisture content throughout the clay mass during the drying operation.

By applying radiant energy, it is possible to heat a clay mass of considerable thickness to a uniform temperature throughout both the interior and surface portions, but unless facilities are provided for removing the moisture from the surface, such a system of drying is limited in time by the natural process of evaporation which is much too slow for practical purposes, and it is an object of the invention to cause migration of moisture from the interior to the surface of a clay body by means of radiant energy, preferably infra-red heat, and to remove such surface moisture continually by means preferably in the form of a relatively cold current of air acting in opposition to the radiant energy, and correlated with the heat applying means in such fashion as to insure removal of moisture from the surface at a maximum speed but always at a rate somewhat slower than that at which the moisture migrates to the surface of the clay, so that a uniform moisture content is retained throughout the clay body both at the surface as well as at the interior, and there is no danger of the surface reaching a higher temperature than the interior, or otherwise causing a crusting, or excessive shrinking, or hardening at the surface.

The invention has for another object to afford a structure which in general includes a housing in which clay bodies are positionable, or movable in a suitable conveyor, coupled with an air duct preferably located at the top of the housing, and arranged to direct a current of relatively cool air downwardly into the housing and around the clay bodies, in conjunction with chambers arranged at the top and on opposite sides of the air duct and also at opposite sides of the housing, preferably open at both ends to permit movement of air outwardly from the housing, and containing radiant energy units preferably in the form of infra-red electric heaters, or otherwise, which act to direct radiant energy into the housing and upon the clay bodies which are thereby uniformly heated throughout, causing the moisture within each clay mass to migrate to its surface, the cool air passing to the clay bodies before coming into contact with the heat units and being exhausted from the housing around the heat units through the chambers in which they are contained and thus acting in opposition to the heat units.

To these and other ends, the invention consists in the apparatus that will appear clearly

from the following description, when read in conjunction with the accompanying drawings, the novel features being pointed out in the claims at the end of the specification.

In the drawings:

Fig. 1 is a view in side elevation of an apparatus for partially drying moist clay bodies, incorporating one practical embodiment of the invention;

Fig. 2 is a plan view of the same;

Fig. 3 is a transverse vertical sectional view;

Fig. 4 is an enlarged detail sectional view through a clay pug and its support;

Fig. 5 is an enlarged sectional view showing the adjustable supporting means for one of the heat units, and

Fig. 6 is a bottom plan view of the parts illustrated in Fig. 5.

Referring more particularly to the drawings in which like reference numerals refer to the same parts throughout the several views, and in which there is illustrated an example of one practical embodiment of the invention, the apparatus includes a housing mounted upon a framework including uprights 1 and cross bars 2 carried by the uprights, the housing including a bottom wall 3, side walls 4, and a top wall 5, and being open at both ends. The housing just described affords a tunnel to receive the clay bodies and through which travel the endless conveyors 6 in the form of chains or the like to permit convenient positioning of the clay bodies within the housing. Mounted upon the endless conveyors are plates 7 that are preferably perforated to permit free passage of air therethrough, while 8 designates net-like supports preferably in the form of mats of wire net that are positioned upon the plates 7 by the operator feeding the machine, and which are adapted to receive and support a clay pug 9 after it comes from the pugmill, or a clay insulator or other object after it has been turned or shaped, when it is desirable to extract moisture from the clay, preparatory to heat treatment in a kiln.

In the manufacture of porcelain insulators and similar products, the pugs when they come from a pugmill contain about 22% moisture, and it is necessary to remove about 18% moisture before glazing and firing the article, approximately 4% of the moisture being left in the clay when it is placed in the kiln. For finishing or shaping the clay while green, as by turning or cutting grooves, skirts, or other curved or irregular surfaces, it is necessary to remove only about 4% of the original moisture, leaving approximately 18% to permit handling and shaping the green clay, while after the turning, cutting or other shaping operations are completed, the clay article is again subjected to treatment in the drier for removing an additional 14% moisture, permitting approximately 4% to remain as stated above when the clay is placed in the kiln.

The endless conveyors are operated by any suitable mechanism, not shown, and moved intermittently by automatic mechanism, or at the control of the operator. The wire net supporting mats 8 are placed upon the conveyor plates 7 and the pugs 9 or other clay bodies positioned upon the mats 8 at the feeding end of the machine by an operator and similarly removed at the discharge end of the machine after completion of the moisture removal operation, the timing of the movement of the conveyors being preferably such as to retain a given clay body within the housing for a desired length of time. It will be understood that while this application shows an

apparatus of given length with a certain number of air ducts and heating units to be described presently, the length of the machine may be increased to any desired extent by the use of additional air ducts and heating units arranged similarly to those now to be described.

The general practice heretofore in drying clay bodies of this character has been to place them in a room where they are subjected to currents of air heated by steam coils or similar units and controlled humidity, it being essential not to evaporate moisture from the surface faster than the moisture travels from the interior of the clay body to the surface, because otherwise the surface becomes dry and forms a crust, which results ultimately in cracking the surface, or bursting the insulator when it is subjected to heat treatment in the kiln. To prevent this under the conventional drying process just referred to, it is necessary to proceed quite slowly, and the drying operation requires approximately one hundred and sixty-eight hours or longer to remove the necessary amount of moisture in a manner that will leave the clay in proper condition for firing.

A primary objective of the present invention is to reduce the time required for removing moisture from such clay bodies and to reduce the percentage of loss resulting from improper drying operations, and this is accomplished by employing radiant energy, preferably in the form of energy from a radiant heater, resulting in uniformly raising the temperature of each clay body throughout its entire mass, without the instrumentality of convection or air currents, thus causing a continuous migration of moisture from the interior of each clay body to its surface. The surface moisture is continuously removed by means of a current of air that is relatively cool, or at a somewhat lower temperature than that of the clay body, the cool air traveling over and entirely around the clay bodies and thence toward and around the heating units in a direction generally opposed to the heat rays. The cool air currents thus act in opposition to the beam of radiant energy, or the heat rays and function only to remove the surface moisture from the clay, without raising the temperature of the surface of the clay and without any tendency to cause a crusting of the surface by removing moisture faster than it migrates from the interior to the surface.

This is attained by a series of radiant heating units located in chambers 11 disposed at the top of the housing on opposite sides of the air duct to be described presently. The chambers 11 are preferably inclined in opposite directions as shown, and communicate with the housing at their inner ends while preferably though not necessarily open at their outer ends, while 12 designates similar chambers located at opposite sides of the housing, communicating at their inner ends with the housing and preferably though not necessarily open at their outer ends.

These chambers may be arranged at suitable intervals along the housing, the chambers 11 at the top being staggered with reference to the chambers 12, as shown in Fig. 1, and suitably spaced from each other endwise of the housing, each chamber being provided with a heating unit 13 preferably consisting of an infra-red electric heater employing a carborundum resistor or "Globar" element, to which current is supplied in any suitable fashion. It has been ascertained that the energy from the infra-red region of the

spectrum is best adapted to present purposes, although it is possible to employ other types of radiant heaters such as a carbon electrode lamp, an incandescent carbon filament lamp, high pressure steam within pipes, or oil burners within pipes or indirectly heating through radiant surfaces, the necessary qualification being that the energy is transmitted in such a manner as to elevate the temperature of the clay and to maintain a substantially uniform degree of moisture throughout each clay body to insure maintaining a temperature at the interior of the clay body as high as the temperature at its surface. By this means, it is possible to insure continuous and uninterrupted migration of moisture to the surface and to prevent effectually any crusting or excessive drying at the surface.

Each heating unit 13, consisting of an infrared carborundum resistor heater, as described above, is suitably supported upon an adjustable standard 14, see Fig. 6, which is mounted in the opposite walls 15 and 16 of the chamber and slidably adjustable in slots 17 so that each heating unit, which is preferably provided with a suitable reflector, can be adjusted endwise of its chamber closer to or further away from the housing, and also tilted to vary the general direction of travel of its rays with relation to the clay bodies within the housing.

With this arrangement, radiant-heat is directed on to the clay bodies from both sides and from the top, and in order to remove the moisture from the surface of the clay bodies, air ducts 18 are provided arranged centrally of the top of the housing and extending endwise thereof with tapering reduced ends 19, as shown, while 20 designates fans or blowers operated by any convenient means, one located at the top of each duct and acting to force air downwardly through the duct into the housing. The air that is thus forced into the housing may be taken into the air duct 18 at the top thereof from the room in which the apparatus is located at normal room temperature of from 65° F. to 70° F. and without any control of humidity, although the temperature of the air may be somewhat higher or lower than that stated, so long as the air enters the housing at a temperature considerably less than the temperature induced in the clay bodies by the radiant-heat units. Thus no heat is carried to the clay by convection and the air currents cannot remove moisture from the surface of the clay at a faster rate than it collects upon the surface or migrates from the interior.

The air traveling downwardly through the ducts 18 spreads out within the housing, contacting substantially the entire surfaces of the clay bodies uniformly, and travels thence outwardly from the housing through the respective chambers 11 and 12 and through the open ends of the housing. The air which makes an exit through the chambers 11 and 12 thus contacts the clay bodies before coming in contact with the heating units, thus acting in opposition to the latter, and the air as it enters the housing may be at any desired temperature below that of the clay bodies, provided it is not sufficiently low as to reduce materially the temperature of the carborundum elements of the heating units and lessen the heating effect of the latter.

With an apparatus operating as indicated above, maintaining an ambient temperature within the housing or tunnel of 51° C. and a tem-

perature of the clay bodies of 30° C., it has been possible to remove 1% moisture during each twenty-two minute period, or a total of 18% moisture in approximately six and three-quarter hours without cracking the surface of the clay, or destroying the insulator when fired. The partial drying of the green clay for turning, cutting or otherwise shaping the article has been completed in one and one-half hours, and the complete drying operation in an additional five and one-quarter hours, as compared with a total of one hundred and sixty-eight hours for complete drying with hot air currents passing over steam coils and with controlled humidity. The drying time has been reduced from one hundred and sixty-eight to eight hours, with an attendant reduction of insulator losses, due to cracking the surface of or bursting the clay bodies upon firing, from 3.9% under the hot air drying system to .9% with the present system of radiant energy and relatively cool air currents acting in opposition to the radiant energy and functioning only to remove the moisture from the surfaces of the clay.

The results described are due to the combining in the manner set forth of the two factors of radiant energy and relatively cool air, or air at room temperature, which contacts the clay bodies before reaching the heating units, since it has been determined that if radiant heat is directed upon the clay bodies without utilizing the air currents at lower temperatures to remove the moisture, there is no gain in the drying time over existing methods and such procedure is too slow for practical purposes, while on the other hand, if the air currents are used without radiant energy to raise the temperature of the clay uniformly throughout, moisture is removed from the surface so much faster than it migrates from the interior of the clay that the surface portion forms into a relatively hard dry crust, leaving an excess of moisture in the interior to cause bursting of the body upon firing, or cracking, and rendering the insulator unfit for practical purposes.

While the invention has been described with reference to the particular construction shown, it is not confined to the details or exact procedure set forth, and this application is intended to cover any modifications or departures in the structure that may come within the purposes of the invention and the scope of the following claim.

We claim:

Apparatus for partially drying moist clay bodies comprising a housing, a conveyor movable through said housing, a net-like support for the clay bodies whereby air has access around substantially the entire surfaces thereof, an air duct located centrally above the housing and in communication therewith, a blower acting to force air through said duct into the housing, chambers located above the housing on opposite sides of said duct, chambers located on opposite sides of the housing, said chambers having their inner ends in communication with the housing and open at their outer ends, and radiant-heat units located in the chambers, the air being movable around the clay bodies and thence outwardly through said chambers in a direction opposite to the rays from the heat units.
